SHOE FITTING INDEX

Arnold G. Bartschi, Oakmont, and Robert L. Huffine, Wynnewood, Pa., assignors to J. Edwards & Co., Philadelphia, Pa., a corporation of Pennsylvania

Application February 25, 1935, Serial No. 8,104

5 Claims. (Cl. 36—1)

This invention relates to shoe fitting index, and has for an object to provide means cooperating with the X-ray fitting of shoes for determining with accuracy the proper fit.

5 It is well known that in the modern fitting of shoes, X-rays are employed, and by their assistance, the position of the foot within the shoe accurately determinable. This has added greatly to the proper fitting of shoes, but requires for its 10 efficient employment, highly specialized operatives. The present invention is directed to providing the shoe with such means for cooperating with the X-ray fitting as to enable less skilled operators to successfully fit the foot.

15 At the present time shoes are made upon variously contoured machines for the purpose of fitting various feet, and the determination of the correct last for the foot is one requiring great accuracy.

20 According to the present invention, an index is placed in or on the shoe sole, constructed of material which, in conjunction with X-rays, will be differentiated from the appearance of the foot structure or the shoe structure, and the index 25 will point to or locate some particular important part or feature of the anatomical structure of the foot, whereby the proper positioning of the foot relative to the contour of the shoe will be assured.

The index may be of any material which will 30 show contrast to the foot and shoe structure, but at the present time, seems desirable that it shall be of material substantially opaque to X-rays, such for instance as sheet lead or vulcanized rubber, but without in any way limiting the invention to such materials.

The invention, therefore, comprises employing some marker or pointer embedded in or placed upon the sole of the shoe, and indicating some exact location for the positioning of anatomical 40 parts of the foot, to insure correct fitting of the foot. This may take the form of a pointer which would indicate some prominent anatomical part or other form, without limitation.

The drawing illustrates several embodiments 45 of the invention and the views therein are as follows:

Figure 1 is a perspective view of a shoe with the sole bent backwardly, showing an index embedded within the sole immediately under the 50 outer sole,

Figure 2 is a similar perspective view showing the index placed within the sole, but against the insole,

Figure 3 is a perspective view of an index of 55 different type,

Figure 4 is a perspective view of one form of index,

Figure 5 is a perspective view of another form of index,

Figure 6 is a schematic view of the anatomical 5 structure of a foot employing the index shown at Figure 4, and

Figure 7 is a schematic view showing the anatomical structure of the foot in association with an index, as shown at Figure 5. 10

Like characters of reference indicate corresponding parts throughout the several views.

It is well known that certain materials, among which are lead and vulcanized rubber, are practically opaque to X-rays, and it has been found 15 possible, therefore, to employ an index of some such material embedded in or associated with the sole of the shoe, which will, in association with X-rays, determine the exact positioning of the foot relative to the shoe by indicating whether 20 or not the bony structure of the foot has been properly placed.

As shown at Figure 1, an index 10 is placed within the sole immediately between the outer sole 11 and a filler 12. As shown at Figure 2, 25 the same index is placed next to the insole 13 a part of the interlaying lamina being shown cut and rolled back for the purpose of exhibiting the index. As shown at Figure 6, this index 10 is properly positioned in the shoe to indicate that 30 part shown at 14, which is designed and contoured to accommodate the ball joint of the foot, that is to say, the articulation of the first metatarsal with the phalanges of the great toe. 35

While this joint is of such a nature as to insure the proper fitting of the shoe when properly positioned, it is, of course, obvious that the index may point out other features of the bony structure of the foot with equal or acceptable results.

As shown at Figure 3, the index 15 is shown 40 of arcuate form and is similarly positioned relative to the sole of the shoe, so far as its being embedded therein or applied thereto. This arcuate index is intended to properly locate the anterior metatarsal arch of the foot, as indicated 45 at Figure 7.

While the two types are shown and described, it is obvious that they may assume various other physical forms, and may be associated with the shoe in various other physical conditions. The 50 essence of the invention, however, is in the applying to a shoe an index in any predetermined or effective position, which will properly indicate the position of the foot within the shoe equipped with such index, such index to be made of any 55

appropriate or desirable material now known or hereinafter developed, which will contrast with parts of the foot structure or shoe structure when subjected to X-rays.

5. Of course, the shoe fitting index illustrated may be modified and changed in various ways without departing from the invention herein set forth and hereinafter claimed.

We claim:—

10. 1. The combination of a shoe including a sole, a narrow, transversely extending index strip embedded in the sole of the shoe, said index being composed of material visibly differentiated from foot and shoe structure under the action of 15 X-rays, said index underlying the articulation of the first metatarsal and proximate phalange of the great toe.

2. The combination of a shoe including a sole, an index embedded in the sole, said index being 20 composed of material opaque to X-rays and positioned to underlie the proper location of the

articulation of the first metatarsal and proximate phalange of the great toe.

3. The combination of a shoe including a sole, of an index member embedded in the sole, said index being of a material opaque to X-rays and 5 positioned in the sole to underlie the proper location of the articulation of the metatarsal and proximate phalange of one of the toes.

4. The combination of a shoe including a sole, of a metallic index member embedded in the sole 10 and positioned to underlie the proper location of the articulation of the first metatarsal and proximate phalange of one of the toes.

5. The combination of a shoe including a sole, of an index member comprising a narrow trans- 15 versely extending metallic strip embedded in the sole and positioned to underlie the proper location of the articulation of the first metatarsal and proximate phalange of one of the toes.
